UNITED STATES PATENT OFFICE.

OTIS R. TIDBALL, OF LUCAS, KANSAS.

MAIL BOX.

Application filed March 17, 1927. Serial No. 176,130.

The present invention relates to deposit and collection receptacles, and more particularly to mail boxes.

The primary object of the invention is to provide a mail box embodying a base and a box pivotally supported on the base so that the box may be swung forwardly to a position in proximity to the delivery man to facilitate the positioning and removal of articles from the box.

An important object of the invention is to provide a box of this character having a hinged closure for closing one end of the box, the closure being automatically operated by the movement of the box to open or close the closure.

A still further object of the invention is to provide means whereby the operating lever may be moved to hold the box in its forward position so that the delivery man may have the use of both hands in assorting and positioning letters or the like in the box.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a mail box constructed in accordance with the invention.

Figure 2 is a sectional view taken on line 2-2 of Figure 1.

Figure 3 is a vertical sectional view through a mail box constructed in accordance with the invention.

Figure 4 is a sectional view taken on line 4-4 of Figure 1.

Figure 5 is an elevational view illustrating the flag support.

Referring to the drawings in detail, the invention embodies a rectangular supporting frame embodying side rails 5 having downwardly extended flanges adapted to fit over a supporting structure 6, the supporting frame being secured to the supporting structure 6 by means of the bolts 7 and 8 respectively.

The box proper is indicated generally by the reference character 9, the same being provided with straps 10 under which the horizontal rods 11 of the pivoted supports 12 are positioned, the rods 13 thereof being secured to the supporting frame by means of the metallic strap 14 to permit of pivotal movement of the arms with respect to the supporting frame.

Secured to the pivoted supports 12 at the rear of the receptacle, are bars 15 that are of lengths to extend appreciable distances into the box, the bars 15 passing through suitable openings formed in the bottom of the box as clearly shown by the drawings.

Pivotedly connected with the upper ends of the bars 15, are bars 16 that have their forward ends pivotedly connected to the upstanding arms 17 that are secured to the inner surface of the hinged closure 18, to the end that as the pivoted supports 12 swing to a position as shown by Figure 3, the closure 18 will be automatically opened and when the supports 12 move to their vertical positions, the closure 18 will be automatically moved to its closed position.

The body portion or box is returned to its normal position by means of the coiled springs 19, the coiled springs having one of their respective ends secured adjacent to the lower end of the bar 15 associated therewith, while the opposite ends of the springs are connected with the hooks 20 that are hooked around the forward pivoted supporting members 12.

Thus it will be seen that when the box or body portion is moved forwardly, the springs are placed under tension. Secured to one of the rods of the pivoted support 12 positioned adjacent to the front of the machine is a lever 21 that is mounted for slight pivotal movement with respect to the support. A locking finger indicated at 22 forms a part of the connecting member that connects the lever 21 to its pivotal support, to the end that when the lever is swung downwardly, the finger will engage the upper surface of one of the bars of which the supporting frame is constructed to lock the box in its forward position so that the delivery man may have the use of both hands in assorting and positioning articles.

The reference character 23 indicates a chain that has one end connected with the under side of the mail box as shown by Fig-

ure 3, the opposite end thereof being connected to one of the cross bars of the supporting frame at 24, with the result that when the springs move the box or body portion to its initial position, the chain will be tightened to restrict movement of the box or body portion to insure the box or body portion being held in its upright position.

At one side of the body portion is a tubular staff support indicated at 25, the same being provided with a curved slot formed in the wall thereof, which slot has an offset upper extremity 26 for the reception of the stud 27 that extends laterally from the staff 28 on which the signal or flag 29 is mounted.

The stud 27 is of a length so that it may be readily gripped by the deliveryman or person placing an article in the box, to raise or lower the signal.

The staff 28 extends through openings in the upper and lower ends of the support 25 and it will be obvious that as the staff is moved vertically, the staff and its flag 29

which are formed preferably of metal, will be rotated so that the flag will be properly displayed and may be viewed by persons some distance from the box.

I claim:

In a deposit and collection receptacle, a supporting frame, supports pivotally connected with the supporting frame, a box pivotally connected with the supports, a lever connected with one of the supports and mounted for pivotal movement with respect thereto, a finger carried by the lever and adapted to engage one of the supports to hold the box in its downward position, a closure for the box, said closure adapted to simultaneously open with the downward movement of the box, and means for returning the box to its upright position.

In testimony that I claim the foregoing as my own, I have hereto affixed my signature.

OTIS R. TIDBALL.
